[57] CLAIM

The ornamental design for a planter, as shown and described.

DESCRIPTION

FIG. 1 is a front elevational view of a planter showing my new design, the side and rear views (not shown) being identical thereto;

FIG. 2 is a top plan view;

FIG. 3 is a bottom plan view; and,

FIG. 4 is a perspective view.

The broken lines of FIG. 4 showing an arrangement of flowers and plants, and soil, are for illustrative purposes only and form no part of the claimed design.

FIG. 3

FIG. 2

FIG. 4

FIG.1
